(57) **CLAIM**

The ornamental design for a charging case, as shown as described.

DESCRIPTION

This application is related to co-filed U.S. utility patent application Ser.No. 14/790,054, the contents of which is hereby incorporated in its entirety.

FIG. 1 is a perspective view of a charging case showing our new design, in a closed condition;

FIG. 2 is a top plan view thereof;

FIG. 3 is a front elevational view thereof, the rear side being a mirror image thereof;

FIG. 4 is a side elevational view of one side thereof; and,

FIG. 5 is a side elevational view of the opposite side thereof. The broken lines in the drawings are included for the purpose of illustrating portions of the article and form no part of the claimed design.

1 Claim, 2 Drawing Sheets
